[57] CLAIM

The ornamental design for a bed clothes support, as shown and described.

DESCRIPTION

FIG. 1 is a front, top and side perspective view of the bed clothes support embodying the design of the present invention;

FIG. 2 is an end elevational view thereof, the end opposite being a mirror image of the end shown in FIG. 2;

FIG. 3 is a front elevational view thereof;

FIG. 4 is a rear elevational view thereof;

FIG. 5 is a top plan view thereof; and,

FIG. 6 is a bottom plan view thereof.

FIG. 1.

FIG. 3.

FIG. 4.

FIG. 2.

FIG. 5.

FIG. 6.
